UNITED STATES PATENT OFFICE.

JOHN E. HANIFEN, OF PHILADELPHIA, PENNSYLVANIA.

DESIGN FOR ORNAMENTAL STOCKING FABRIC.

SPECIFICATION forming part of Design No. 11,729, dated April 13, 1880.

Application filed November 29, 1879. Term of patent 3½ years.

To all whom it may concern:

Be it known that I, JOHN E. HANIFEN, of the city and county of Philadelphia, and State of Pennsylvania, have originated and designed 5 an Ornamental Stocking Fabric, of which the following is a full, clear, and exact description, reference being had to the accompanying photographic illustration, making part of this specification.

10 Parallel rows of plain stitches a extend in straight continuous lines across the fabric. These rows are of dark color, and alternate with straight light-colored or white rows c of plain stitches. Longitudinal straight lines of 15 tuck-stitches b extend through the fabric, crossing the said transverse rows of stitches a and c. These tuck-stitches are somewhat lighter in color than dark stitches a, or they may be of the same tint, and hence do not show distinctly except upon the white or light ground 20 of plain stitches c. They are arranged so as to form stripes of broken lines, each line being separated from its neighbors by an alternating line of the stitches c, and each stripe as 25 a whole being separated from its neighbors by a belt of light stitches. Hence the general effect is that of a number of longitudinal stripes, equal in width, of tuck-strokes arranged in isolated broken lines, with alternating light-colored broken lines of plain stitches (single between the tuck-lines and broader between the tuck-strokes) and transverse straight bars of continuous lines of dark plain stitches. 30

I am aware that the design patent of Dela-henty, June 2, 1868, No. 3,062, shows a fabric 35 having a plain white background, and stitches of darker color arranged in lines forming stripes thereon. I do not claim said design.

What I claim is—

The design for ornamental stocking fabrics, 40 consisting of plain white or light-colored stitches c, forming the background, unbroken transverse straight lines of tuck-strokes a, arranged at intervals, as shown, and longitudinal straight broken lines of tuck-strokes b, 45 having the lines separate, but forming stripes of equal width at intervals, as shown.
